MACHINES FOR FORMING ATTACHING FACES OF WEDGE HEELS

Edgar E. Joiner, Jr., Andover, Mass., assignor to United Shoe Machinery Corporation, Flemington, N. J., a corporation of New Jersey

Application September 11, 1953, Serial No. 379,558

19 Claims. (Cl. 144—145)

This invention relates to machines for forming the attaching faces of wedge heels. It is an object of the present invention to provide an improved machine of the general type disclosed in United States Letters Patent No. 2,613,705, granted October 14, 1952, on an application filed in the names of Harley W. Russ and Edgar E. Joiner, Jr., for forming, on the upper face portions of wedge heel blocks, attaching faces substantially complementary to the heel seat and shank portions of the bottoms of platforms of full-fashioned platform shoes to which wedge heels, subsequently formed from the blocks, are attached.

The present invention consists in the novel features hereinafter described, reference being had to the accompanying drawings which illustrate one embodiment of the invention selected for purposes of illustration, said invention being fully disclosed in the following description and claims.

In the drawings,

Fig. 1 is a side view of an illustrative machine in the process of forming upon a heel block an upper or attaching face which is approximately complementary to the shank and heel seat portions of the bottom of a full-fashioned platform shoe to which a wedge heel, subsequently turned from said block, is to be attached;

Figs. 2 and 3 are front and plan views, respectively, partly broken away and partly in section, of the machine shown in Fig. 1;

Fig. 4 shows in side elevation heel block guiding and trimming instrumentalities of the machine in the process of forming a shank portion of the attaching face of the heel block which is subsequently "turned" to form a right wedge heel;

Fig. 5 is a view similar to Fig. 4 but showing the machine operating upon the heel block from which a left heel is subsequently formed;

Fig. 6 is a view on the line VI—VI of Fig. 1 showing a work holder, in which the heel block has been positioned and clamped, being guided past a rotary cutter to cause said block to traverse said cutter to form an attaching face on said block;

Fig. 7 shows portions of the mechanism illustrated in Fig. 6 as viewed on the line VII—VII of Fig. 1;

Fig. 8 is a plan view of one of a pair of identical patterns which are secured respectively to upper and lower portions of a work carrier of the machine when it is desired to form on the heel block an attaching face of a conventional type;

Figs. 9 and 10 show in plan patterns which are secured interchangeably to the upper and lower portions respectively of the work carrier of the machine adapted to tilt the heel block laterally as a shank portion of its attaching face is being formed, thereby providing an attaching face which is complementary to the heel seat and the shank portions of the bottom of the platform of the full-fashioned platform shoe;

Fig. 11 is a view on the line XI—XI of Fig. 2 illustrating a coupling unit of the machine in the process of being

2

moved between two operating positions in which it is secured to a yoke to adapt the machine for operating upon right and left work;

Fig. 12 is a section on the line XIII—XII of Fig. 3;

Fig. 13 is a section on the line XIII—XIII of Fig. 12; Figs. 14 and 15 are sections on the lines XIV—XIV, XV—XV, respectively, of Fig. 13;

Fig. 16 is a front view of mechanism for operating a shield or guard which is positioned in front of the rotary cutter of the machine when said machine is not in use;

Fig. 17 shows in perspective a heel block which is to be operated upon by the illustrative machine;

Fig. 18 is a perspective view of the block illustrated in Fig. 17 after it has been operated upon by the illustrative machine, a wood heel subsequently turned from the block being shown in phantom;

Fig. 19 shows in perspective the wood heel which is formed from the heel block shown in Fig. 18;

Fig. 20 is a perspective view of a portion of an inverted full-fashioned platform shoe, the heel shown in Fig. 19 being shown in phantom on the shoe; and

Figs. 21 and 22 are sections through the shoe and its attached heel as viewed on lines XXI—XXI, XXII—XXII respectively of Fig. 20.

The illustrative machine is described with reference to trimming material from the upper face portion 30 (Fig. 17) of a wedge heel block 32 to form a partially trimmed heel block 32a (Fig. 18) having an upper or attaching face 34 a portion of which (outlined in phantom) is approximately complementary to the heel seat and shank portions 36, 38 respectively of a platform 40 (Figs. 20, 21 and 22) which has been stitched to the bottom of a lasted full-fashioned shoe 42 and to which a heel 44, turned from the block 32a and thereafter covered, is subsequently secured. After the heel block 32a has been formed by the use of the illustrative machine, material is trimmed from the side and rear faces of the block by the use of a wood heel turning machine (not shown) to produce the wedge heel 44.

The face 34 of the heel block 32a comprises a heel seat portion 39 which is slightly concave transversely and is also slightly concave longitudinally at its rear end, and which is defined by a margin 48 corresponding to a heel seat rim 50 of the wood heel 44 and arranged approximately in a plane. The face 34 also includes a shank portion 52 which is separated from the heel seat portion 39 by a heel breast line 46 and is concave transversely and which is defined by an inner or instep margin or line 54 and an outer margin or line 58, said instep line 54 corresponding to an inner or instep edge or rim 56 of the heel 44, and said outer line 58 corresponding to an outer edge or rim 60 of a shank portion 61 of an upper or attaching face 62 of the heel, different portions of the inner or instep line 54 being higher than laterally opposed portions of said outer line 58. In the finished heel 44 different portions of the rim or edge 56 of the shank portion 61 of the upper or attaching face 62 of the heel are higher than transversely opposite portions of the outer rim or edge 60 of said shank portion of the heel, said face 62 being shaped to "form fit" the heel seat and shank portions 36, 38 of the bottom of the platform 40 of the full-fashioned shoe 42. Sides 63, 63a and 65, 65a of the blocks 32, 32a respectively from which material is trimmed during the forming of the inner and outer sides of the heel 44 will be described as the inner and outer sides respectively of the heel blocks.

When the heel 44 is properly positioned upon and secured for example, by an adhesive to the heel seat and shank portion 36, 38 of the platform 40 of the shoe 42, the inner and outer rims or edges 56, 60 of the heel 44, as well as the rim 50 of a heel seat portion 71 of the face 62 of the heel, hug the platform 40 which is conformed

to the heel seat and shank portions of the bottom of the lasted shoe 42. The shank and heel seat portions 61, 71 of the upper face 62 of the heel 44 are separated by a heel breast line 46a corresponding to the heel breast line 46.

The shank and heel seat portions 38, 36 respectively of the platforms 40 of full-fashioned shoes 42, which are of different sizes and styles and into which lasts 43 have been "slipped," are of different shapes and it is desirable that the upper faces 62 of the heels shall be formed substantially complementary to said shank and heel seat portions of the platforms, thereby insuring that the heels shall merge gracefully with and shall effectively support the shoes. The longitudinal contour of the outer margin of the shank portion 38 of the bottom of the platform 40 is generally similar to the longitudinal contour of a median line along said shank portion and the longitudinal contour of the inner or instep margin of the shank portion of the bottom of the platform 40 is raised somewhat with relation to a transversely opposite portion of the outer margin of said shank portion. Accordingly, in order that the heel shall hug the instep of the shank portion of the platform, portions of the inner edge of the shank portion 61 of the attaching face 62 of the heel are formed higher than corresponding opposite portions of the outer face 60 of said shank portion, as above described. The transverse concavity of the attaching faces 62 of the heels 44 may be varied, in accordance with the size and style of the shoe to which the heel is to be attached, by using in the illustrative machine a rotary cutter 70 of the desired shape. In order that the shank portions 61 of the attaching faces 62 of heels 44, which are to be attached to full-fashioned platform shoes 42 of different sizes and styles, shall be effectively formed to shapes complementary to the shank portions 38 of the bottoms of the platforms 40 of the shoes, I have found that it is desirable, as the heel block 32 traverses the cutter 70 to form the shank portion 52 of the attaching face 34 of the block 32a and accordingly the shank portion 61 of the attaching face 62 of the heel 44, to tilt the heel block 32 laterally away from the cutter about an axis 72 which extends generally lengthwise of and substantially along the outer margin of the shank portion of the attaching face being formed on the block. The illustrated machine is adapted quickly and effectively to form heel attaching faces 34 on heel blocks 32 which are of different lengths, widths, heights and/or pitches and from which form fitting wedge heels 44 of different sizes and styles may be turned.

In order to form the attaching face 34 upon the heel block 32 to provide the partially completed block 32a, said block 32, secured to a carrier 64, which is journaled on a yoke or mount 67 in turn journaled upon an adjustable supporting slide or bracket 69 (Figs. 2 and 3), is manually swung about two spaced parallel or vertical axes 66, 68 to allow the heel block to traverse the rotary cutter 70, which has an axis 73, in a predetermined path controlled by means hereinafter described. The block 32 is held against lateral tilting as the heel seat portion 39 of its face is being formed but, as the shank portion 52 of its face is being formed, is tilted laterally about the horizontal axis 72 then extending generally lengthwise of and along the outer margin 58 of said shank portion. The line 58 is arranged in close proximity to a shank portion of an outer edge 74a of the face 34 of the block 32a as well as in close proximity to the previously existing shank portion of an outer edge 74 of the upper face portion 30 of the block 32 and accordingly the block 32 or 32a as it traverses the cutter 70 may be described as being tilted laterally about an axis extending generally lengthwise of the upper outer corner portion of the block.

Rotatably mounted in a bearing boss 76 (Fig. 1) of a main frame 78 of the machine and driven by an electric motor 80 secured to said frame is a vertical spindle 82.

The spindle 82 has a shoulder 84 (Figs. 1, 4 and 5) on which rests an interchangeable spacer 86 and clamped by a screw 89 between a lower clamping collar 88 which rests on the spacer 86, and an upper clamping collar 88a are a pair of cutting blades 90 having cutting edges 92 which are convex lengthwise and which, when the cutter is rotated, generate a barrel-shaped surface or locus 94. The cutting blades 90 which fit in grooves 96, 98 of the collars 88, 88a respectively may be replaced by cutting blades 90 having edges 92 of different lengths and curvatures in accordance with the width of the heel block 32 to be operated upon and the desired transverse concave curvature of the face 34 of the heel block 32a.

Secured by screws 100 (Fig. 1) in different forward and rearward adjusted positions in a horizontal rectilinear guideway 102 of the main frame 78 is a lower abutment, rub plate or rub collar 104 (Figs. 1, 4 and 5) having a cylindrical face 106 vertical elements of which, when the machine is at rest, are coincident with vertical lines 108 respectively extending vertically through a maximum circumference 110 of the locus 94 of the cutting edges 92 of the cutter 70 which collectively may be referred to as a cutter head.

Secured in different operative positions in a rectilinear guideway 112 (Fig. 3) of a bracket 114 is an upper abutment, rub plate or rub collar 116 provided with slots 118 through which pass clamping screws 120 which are threaded into the bracket and which, after the rub collar has been properly positioned in the bracket by the use of an adjusting screw 121, are screwed down to clamp the rub collar to hold it in its adjusted position in the guideway 112.

In order to allow the cutter head of the machine to be changed, it is desirable to move the rub collar 116 away from its operative or active position shown in Figs. 1, 3, 4 and 5 and accordingly the bracket 114 is fulcrumed on a pair of bearing screws 122 in the main frame 78. The bracket 114 has formed in it a slot 124 for receiving a screw 126 which may be rotated into a position in which it permits the bracket to be swung from its horizontal active position to a raised, inactive position (not shown). After the bracket 114 has been swung into its active position against a stop face 148 of the main frame 78, the screw 126 is rotated to its position shown in Fig. 3 to secure the bracket and accordingly the rub collar 116 in its active position. The upper rub collar 116, as in the case of the lower rub collar 104, is so constructed and arranged that elements of a cylindrical face 130 thereof are approximately coincident with the vertical lines 108 intersecting the maximum circle 110 of the locus 94 which circle is included in a horizontal plane 129 which may be described as the transverse median plane of the cutter. The cylindrical faces 106, 130 of the rub collars 104, 116 respectively may be defined as being arranged coaxially with or in concentric relation to the cutter 70 and as being arranged at opposite ends of the cutter.

In order to hold the cutter spindle 82 against rotation when the cutter 70 is being changed, there is provided a foot actuated lever 132 (Fig. 1) which is fulcrumed upon a pin 134 secured to the main frame 78 and which may be forced against a concave surface 136 at the lower end of the spindle 82.

Movable along a vertical dovetail guideway 138 (Figs. 2 and 3) of the main frame 78 of the machine is the adjustable supporting slide or bracket 69 into which is threaded an elongated screw 142 journaled in the main frame 78 and which has secured to it a bearing pin 144. Journaled upon the bearing pin 144, which may be considered part of the supporting slide 69, for movement about the axis 68 and supported upon a thrust bearing 146 (2) is a suspension or bearing block 148 having threaded into it a bearing stud 150 on which is secured by a nut 152 a ball bearing 156. Mounted upon the ball bearing 156 is a coupling unit 160 which comprises a dovetail-guide 162 normally secured by interlocking means

comprising retaining screws 164 to the yoke 67, said unit being retained on the bearing block by a ring 154 secured to and forming part of a housing 158 of said unit. The suspension block 148 and the yoke 67 may be referred to as a mount.

The housing 158 of the coupling unit 160 has formed in it a pair of horizontally disposed guideways 168 in which are mounted latches 170 having cylindrical ends 172 one of which at a time is active and, when it is desired rigidly to lock the housing to the bearing block 148, fits in a cylindrical bore 174 of a filler piece 176 fitting in a notch 178 of a forwardly projecting flange 180 of the block 148. When it is desired to tilt the coupling unit 160 and accordingly the yoke 67 to which said unit is secured about the axis 72 with reference to the bearing block 148, the filler piece 176 is removed from the notch 178, the cylindrical end 172 of the forward of the two latches 170 then being free to move slightly between upper and lower faces of the notch. With the above described construction the carrier 64 is permitted to swing, tilt or rock a few degrees in opposite directions about the axis 72, the swinging movement being limited by the engagement of the cylindrical end 172 of the forward latch 170 with upper and lower faces of the notch 178.

Threaded into the yoke 67 is a bearing stud 182 which fits in a stepped recess 184 (Figs. 3, 12 and 13) in the dovetail guide 162 and has a horizontal axis 186 which may be referred to as an adjusting axis and is usually offset a distance 187 (Fig. 12) above or below the axis 72 in accordance with the setting of the coupling unit 160 for right or left work, as will be explained later. The forward latch 170 is manually slid between an active position in which its cylindrical end 172 enters the bore 174 of the filler piece 176 or if the filler piece 176 is removed from the notch 178 enters the notch, and an inactive position in which the entire latch is retracted into its guideway 168, by the use of a pin 188 which is secured to the latch and extends through a slot 190 (Figs. 2 and 13) formed in an adjacent portion of the housing 158. Each of the latches 170 is retained in its active and inactive positions along its guideway by a spring-pressed ball 192 slidably mounted in the housing 158 and engaging in either one of two notches 194 in the latch.

Fixed to the dovetail guide 162 of the coupling unit 160 is a plate 196 in which is journaled an adjusting screw 198 threaded into the housing 158 of said unit to enable the dovetail guide and accordingly the bearing stud 182, to which the yoke 67 is secured, to be moved toward and away from the axis 72 of the bearing stud 150 in accordance with the width of the heel block 32 being operated upon, the distance 187 between the axes 186 and 72 being equal to one-half the width of the heel block 32 to be operated upon for reasons which will be apparent later. In order that the machine, adjusted for operating upon left work as illustrated in Figs. 5 and 12, may be adjusted for operating upon right work for example, the retaining screws 164 are turned out of threaded bores 199 (Fig. 12) of the dovetail guide 162 and are withdrawn from said guide. The coupling unit 160 is then rotated counterclockwise, as viewed in Fig. 11, 180° about the bearing stud 150 and accordingly about the axis 72, said unit carrying with it the yoke 67 which, because it has little tendency to rotate and is usually held by the operator, rides upright, the axis 186 of the bearing stud 182 moving in a path 201 about the axis 72 as illustrated in Fig. 11. The retaining screws 164 are then threaded into the opposed threaded bores 199 of the dovetail guide 162 to secure the yoke 67, in a lowered operating position, to the coupling unit 160. The coupling unit 160 may be described as being rotatable about the tilt axis 72 to move the yoke 67 selectively between two different operating positions in which the transfer axis 186 is positioned equal distances from and at diametrically opposite sides of the tilt axis.

The carrier 64 comprises an upper portion 200 upon

which is pivotally mounted a work clamp 202 and to which is adjustably secured either a pattern 204 or a pattern 210, and a lower portion which has adjustably secured to it a work holder 208 and has secured to it in a fixed position either the pattern 204 or 210. The patterns 204, 210 are secured to the upper and lower portions 200, 206 respectively of the carrier 64, as illustrated in Fig. 4, when right work is being operated upon and the patterns 204, 210 are secured to the lower and upper portions 206, 200 of the carrier, as illustrated in Fig. 5, when left work is being operated upon. The upper and lower portions 200, 206 of the carrier 64 are normally secured together by screws 212 (Fig. 1) which are threaded into the upper portion of the carrier and extend through an elongated slot 214 in the lower portion of the carrier, the upper portion of the carrier straddling and fitting in guideways 216 formed in the lower portion of the carrier. The upper portion 200 of the carrier 64 is provided with a scale 215 for use in adjusting the lower portion 206 of the carrier heightwise relatively to said upper portion to accommodate heel blocks 32 which are of different widths as will be explained later.

Secured to and forming part of the upper portion 200 of the carrier 64 is a trunnion 218 which fits rotatably in a bore 220 in the yoke 67 and has threaded onto it a nut 222, a thrust bearing 224 being interposed between the nut and the yoke. Secured to and forming part of the lower portion 206 of the carrier 64 is a trunnion 226 which fits rotatably in a bore 228 of the yoke 67 and has secured to its lower end by a clamp screw 230 a stop lug 232. The trunnion 218 has formed on it a scale 219 for use in centralizing, by turning the nut 222, the carrier 64 as an entirety in the yoke 67, said carrier being adjusted in the yoke lengthwise of the trunnions, which have the common axis 66, until a longitudinal median plane 221 of the block lies in the horizontal median plane 129 of the cutter 70. It will be noted that when the carrier 64 and the heel block 32 are centralized in the yoke 67 the axis 186, which may be described as the transfer axis, lies in the plane 221 of the heel block 32 secured in the carrier. The mount 67 may be described as being journaled for arcuate movement, that is movement in which all portions thereof move simultaneously through equal concentric arcs about the tilt axis 72 which is disposed at approximately right angles to the fixed axis 68 and is constrained for arcuate movement about said fixed axis. The swing axis 66 may be described as being fixed with relation to the mount 67 and as being constrained or journaled for arcuate movement about the tilt axis 72.

The yoke 67 is swung manually about the bearing pin 144 and accordingly about the axis 68 by the operator who grasps with his left hand a grip 223 (Fig. 2) which is mounted on a bracket 225 secured by screws 227 to the yoke. The carrier 64 is manually swung upon the yoke about the axis 66, which may be described as the carrier axis, by the operator who grasps in his right hand a handle 233 (Figs. 1 and 2) which is secured by screws 235 to the lower portion 206 of the carrier. By simultaneously moving the yoke 67 about the axis 68 and the carrier 64 about the axis 66, which is parallel to the axis 68 and shifts with the yoke, the heel block, positioned upon and secured to the carrier and guided, controlled or governed by the engagement of the patterns 204, 210 with the rub collars, may be moved in a predetermined path past the cutter 70 to form the face 34 on the heel block 32a. In order to relieve the operator the yoke 67 may be rotated about the axis 68 by fluid pressure means similar, for example, to that shown in the above-mentioned Patent No. 2,613,705.

Fulcrumed on a pin 234 secured to the upper portion 200 of the carrier 64 is a bell crank lever 236 having a lower arm grooved to receive the clamp 202 which may be secured in different adjusted positions to the arm by screws 238 threaded into said arm and passing through

elongated slots (not shown) in the clamp. Secured to the upper portion 200 of the carrier 64 is a cylinder 240 in which is reciprocable a piston 241 formed integral with a piston rod 242 operatively connected to an upstanding arm of the bell crank lever 236. The piston 242 is urged against a stop (not shown) in one direction by a spring, air under pressure being supplied to the cylinder through a line 244 open to a valve 246 secured to the lower portion 206 of the carrier 64.

In order that the cutter 70 which rotates continuously when the machine is powered shall be masked, except when the machine is in use, there is pivotally mounted in the main frame 78 a horizontal shaft 237 (Fig. 16) having secured to it a vertically disposed shield or guard 239 which is normally positioned in its masking position adjacent to and in front of the cutter. Also secured to the shaft 237 is an abutment 241 and an arm 243 which carries a pin 245 fitting in an elongated slot 247 formed in a piston rod 249 which is reciprocable in an air cylinder 251. Secured to the frame 78 is a stop 253 and surrounding the shaft 237 and having its opposite ends engaging the guard and the main frame 78 is a coil spring 255 for constantly urging the guard clockwise, as viewed in Fig. 16, until a shoulder 257 of the abutment 241 engages the stop 253 to retain said guard in its masking position. When air is admitted under pressure through a line 259 to the cylinder 251, the piston rod 249 moves to the right, as viewed in Fig. 16, causing the guard 239 to be swung counterclockwise with the shaft 237 until a shoulder 261 of the guard 239 engages the stop 253.

Compressed air is supplied through a line 263 (Fig. 1) to the valve 246 which is operated by a trigger 265 fulcrumed on the valve and overlying the handle 233. As the operator positions the heel block 32 in the holder 208 he grasps the handle 233 and depresses the trigger 265 thereby causing air under pressure to be admitted to the cylinders 240 and 251 with the result that the clamp 202 retains the block securely in the holder 208 and the guard 239 is swung counterclockwise, as viewed in Fig. 16, to its inactive position from in front of the cutter 70.

The lower portion 206 of the carrier 64 comprises a platform 248 which is provided with a rectilinear channel 258 (Figs. 6 and 7) adapted to receive a depending flange of a plate 254 and has elongated slots 252, said plate being secured to the platform in different adjusted positions lengthwise of the channel by bolts 256 which pass through the slots and are threaded into the plate. The upper rear portion of the plate 254 is rabbeted and has secured to it by screws 260 a block support or ledge 262 having a planar serrated upper face arranged horizontally. Secured to the plate 254 is a vertically disposed bearing rod 264 having journaled on it a sectoral rest 266 which is slidably supported on the plate and may be set in different positions about the bearing rod by the use of a screw 268 which is threaded into the plate 254 and passes through an arcuate slot 270 formed in the rest. The sectoral rest 266 has a vertical flange 272 provided with horizontally disposed slots 274 (Figs. 2 and 6) through which pass screws 276 (only one shown) threaded into a backing board 278 which may be secured in different lengthwise positions along the rear face of said flange. Secured by screws 20 to the vertical flange 272 of the sectoral rest 266 is a guide bar 282 in a recrectilinear guideway 284 of which is mounted a slide 285 having a slot 287 for receiving a screw 289 threaded into the guide bar and serving to secure the slide to said bar. The slide 285 has formed in its upper face a rectilinear guideway 291 which is arranged at right angles to the guideway 284 and has adjustably secured to it by a screw 293 an end gage 286. When the heel blocks 32 are not cut to predetermined standard lengths they are positioned lengthwise in the holder 208 by engagement of their rear ends with the gage 286 which may be quickly and effectively set in different positions lengthwise of

the guideway 284 by the use of a scale 292 formed upon the vertical flange 272 of the sectoral rest 266.

The heel block 32 is supported in the machine, as best shown in Figs. 1, 4, 5 and 6, one side of the block resting upon the planar serrated upper face of the block support 262 and the tread or bottom face of the block resting against the backing board 278, the clamp 202 being forced against the other side of the block to hold said block in place.

In order to insure against the carrier 64 being moved into engagement with the cutter 70 because of the carrier being swung on the yoke beyond predetermined limits, the amount of pivotal movement of the carrier about the axis 66 is limited by mechanism which will now be described. Secured by screws 295 (Figs. 2 and 3) to the yoke 67 is a bracket 297 having threaded through it a stop screw 299 which may be set in different adjusted positions in the bracket. Secured by screws 301 to the lower portion 206 of the carrier 64 is a depending abutment 303 which, when the carrier 64 is swung in a clockwise direction as viewed from above (Fig. 3) about the axis 66, engages the stop screw 299 to limit movement of the carrier in said direction upon the yoke 67. Counterclockwise rotation, as viewed in Fig. 3, of the carrier 64 on the yoke 67 is limited by the engagement of the stop lug 232 with a shoulder 305 of the yoke.

When the wedge heel blocks 32 have been pretrimmed or cut to the desired length they are positioned lengthwise on the holder 208 by gaging from their forward ends.

Accordingly, the yoke 67 has secured to it by screws 294 (Figs. 2, 3 and 6) a post 296 upon which is mounted for vertical adjustment a block 298 having at its upper end a guideway 300 for a T-shaped support 302 slotted to receive a screw 304 threaded into the block. Threaded into the T-shaped support 302 and extending through an arcuate slot 306 in an end gage 308 are screws 310 which may be used to set the end gage in the desired position upon the T-shaped support. It will be noted that the end gage 308 is secured to the yoke 67 and accordingly when said end gage is used to position the heel blocks lengthwise in the holder 208 the depending abutment 303 secured to the carrier 64 is held in engagement with the stop screw 299.

In order to balance the yoke 67 so that it will be maintained yieldingly in an upright position but may be tilted about the axis 72 in response to the action of the patterns 204, 210 against the rub collars, there is secured by screws 312 to the yoke a bar 314 in an outer end of which is formed a notch 316. Secured by screws 318 (Fig. 3) to the bearing block 148 is a bar 320 through a bore in an outer portion of which extends a screw 322 having threaded onto it a nut 323 supported by the bar. To the lower end of the screw 322 is attached a spring 324 which carries a latch pin 326 (Fig. 2) shaped and arranged to be locked in the notch 316 so as yieldingly to support, through the bar 314, the yoke 67 in a substantially vertical or neutral position. Preparatory to setting up the machine, which is adjusted to operate upon left work for example, for operating upon right work, or vice versa, the latch pin 326 is removed from the notch 316, said pin being later inserted in said notch and the screw 322 being raised or lowered in the bar 320 sufficiently to apply to the bar 314 the desired amount of biasing force necessary to maintain the yoke 67 yieldingly in its vertical position. As above explained, in operating upon heel blocks 32 from which right heels 44 are to be formed the patterns 204, 210 are secured to the upper and lower portions 200, 206 respectively of the carrier, as shown in Fig. 4, and in operating upon blocks 32 from which left heels 44 are to be formed the patterns 210, 204 are secured to the upper and lower portions 200, 206 respectively of the carrier 64.

Fitting in a vertical channel 328 in the upper portion 200 of the carrier 64 is an angle bracket 330 which has a vertical slot 332 (Fig. 2) through which passes a screw

334 threaded into the carrier, said screw being loosened preparatory to adjusting the bracket to the desired height along the channel and being tightened to secure the bracket to the carrier. The patterns 204, 210 are formed to operate equal distances at opposite sides of heel blocks 32 of different widths and since the distance between the heel block support or ledge 262 and the rabbet 344 is fixed, it will be apparent that the angle bracket 330 has to be initially raised or lowered into different adjusted positions in the channel 328 in accordance with the width of the heel block being operated upon. The heightwise adjusted positions of the brackets 330 in the channel 328 for accommodating heel blocks 32 of different widths may be readily determined by the use of a scale 331. The patterns 204, 210 also fit interchangeably in the rabbet 344 of the lower portion 206 of the carrier 64 and after being positioned lengthwise in the rabbet by alining the groove 338 or 338a formed on the patterns 204, 210 respectively with a groove (not shown) on the carrier 64, are secured to said lower portion of the carrier by a plate 346 clamped against the patterns by screws 348.

The patterns 204, 210 have laterally bowed rub collar engaging faces 352 (Fig. 9), 352a (Fig. 10), respectively comprising heel seat forming portions 356, 356a, which have identical longitudinal contours, profiles or outlines, and shank forming portions 358, 358a which have different longitudinal contours, profiles or outlines, the differences in said contours of said shank forming portions being best illustrated in Fig. 3 which shows the patterns in vertical alinement. The longitudinal contours of the patterns 204, 210 respectively vary in accordance with the sizes and styles of the heels which are to be formed from the heel blocks 32. In order that the rear end of the attaching face 34 of the heel block 32a shall be concave longitudinally, the faces 352, 352a, of the patterns 204, 210 are provided with "run-in" forming portions 360, 360a and in order that the heel block, after the forming of the forward end of the shank portion 52 of the attaching face 34, shall be guided away from the cutter in a controlled path, the faces 352, 352a of the patterns are provided with "run-off" portions 362, 362a.

In view of the foregoing it will be apparent that during the forming of the heel seat portion 39 of the attaching face 34 of the heel block 32a there will not be any tilting of the carrier 64 about the axis 72 since the heel seat forming portions 356, 356a of the patterns 204, 210 are identical and in vertical alinement and the cylindrical faces 130, 106 of the rub collars 116, 104 respectively are also in vertical alinement. In view of the fact, however, that the shank forming portions 358, 358a of the patterns 204, 210 have different profiles, the carrier 64 and accordingly the heel block secured to it (assuming the machine is adjusted for right work as shown in Fig. 4), during the traversing of the heel block past the cutter and in response to the action of the rub collars 114, 116 against the patterns 210, 204, respectively, swings counterclockwise about the axis 72 and away from the cutter to form the shank portion 34 on the heel block 32a. When the machine has been adjusted for left work the patterns 210, 204 are secured to the upper and lower portions 200, 206, of the carrier, as shown in Fig. 5, instead of to the lower and upper portions of the carrier, as shown in Fig. 4, and the carrier swings clockwise as viewed in Fig. 5 about the axis 72 away from the cutter.

It will be noted that when the machine has been adjusted for operating upon right and left work and is trimming material from the upper face portion 30 of the block 32 the tilt axis 72, which is disposed at right angles to and intersects the axis 68, passes substantially through points of intersection of lines passing through portions or elements of simultaneous engagement of the patterns 204, 210 with opposing rub collars and an extension or plane of the outer side 65 of the heel block being trimmed. The carrier 64 may also be described as being tiltable about

an axis which is disposed at right angles to and intersects the axis 68 and which extends in the vicinity of points of intersection of the plane of the block supporting ledge 262 and straight lines extending between portions of simultaneous engagement of the patterns 204, 210 with the rub collars. In Fig. 4, which shows the machine operating upon right work, the outer side 65 of the heel block 32 is the uppermost side of the block in the work holder 208 and in Fig. 5, which shows the machine operating upon left work, the outer side 65 of the heel block is the lowermost side of the block which is secured to the work holder and rests upon the block support or ledge 262 the work engaging portion of which may be described as lying in a plane.

In operating upon right work, as shown in Fig. 4, it is desirable that the uppermost face of the heel block (also the outer side 65 of the block) positioned in the holder 208 shall lie in the tilt axis 72 and in operating upon left work, as shown in Fig. 5, it is desirable that the lowermost face of the block 32 (also the outer side 65 of the block) positioned in the holder 208 shall lie in the tilt axis. In changing over from left to right work or from right to left work of the same width, it is necessary that the heel holder 208 and accordingly the heel block 32 secured to it shall be lowered or raised respectively the width of the heel block so that the outer side 65 or the plane of said face (the uppermost face of the heel in Fig. 4 and the lowermost face in Fig. 5) shall lie approximately in the axis 72. It is desirable that the coupling unit 160, in moving from one to another of its operating positions on the yoke 67 by swinging the bearing stud 182 180° about the tilt axis 72, shall move the yoke 67 lengthwise of the axis 68 (heightwise of the machine) a distance equal to the width of the heel block 32. Accordingly, the screw 198 is initially rotated sufficiently to cause the transfer axis 186 to be raised or lowered relatively to the tilt axis 72 so that said transfer axis lies in the longitudinal heightwise median plane 221 of the block 32 positioned in the machine. When such adjustment has been effected the block 32 positioned and clamped in the holder 208 is raised or lowered the width of the heel block when the coupling unit 160 is moved from one to the other of its operating positions on the yoke 67.

When the machine is to operate upon heel blocks 32 from which are to be formed heels (not shown) to be attached to slip lasted shoes, the bottoms of the platforms of which are flat transversely throughout their widths, said machine is provided with a cutter (not shown) having straight cutting edges and a pair of patterns 364 which are identical and are secured to the upper and lower portions 200, 206 respectively of the carrier 64 in place of the patterns 204, 210. Preparatory to operating on this type of work the filler piece 176 is inserted in the notch 178 of the bearing block 148 and the cylindrical end 172 of one of the latches 170 is inserted in the bore 174 of the filler piece thus locking the coupling unit 160 to the bearing block 148 which is then rigidly secured to and may be considered part of the yoke 67.

Preparatory to operating upon heel blocks 32, which are of different lengths, heights, widths and/or pitches and from which heels 44 are made to fit the heel seat and the shank portions 36, 38 of full fashioned shoes of various sizes and styles, various adjustments hereinafter explained have to be made in the machine.

It will be apparent that in order to form the attaching face 34 upon the heel block 32 said block must be positioned in the machine with its longitudinal heightwise median plane 221 in substantial coincidence with the transverse median plane 129 of the cutter 70 and accordingly the plane of maximum circumference 110 of the locus 94 of the cutting edges 92 of the cutter 70. The patterns 204, 210, as above stated, are profiled on the premise that they are to be positioned equal distances at opposite sides of the heel block 32 positioned in the

machine irrespective of the width of the block and accordingly it is necessary to maintain this condition. Furthermore, the plane of the outer face 65 of the heel block 32 positioned in the machine must approximately include the axis 72, and the transfer axis 186 of the bearing stud 182 must lie substantially in the longitudinal heightwise median plane 221 of the heel block 32 positioned in the machine, the distance between the tilt and the transfer axes 72, 82 being equal to one-half the width of the heel block. It is also desirable that when the patterns 204, 210 are in engagement with opposing rub collars the tilt axis 72, which lies in the plane of the outer side 65 of the heel block, shall substantially intersect the line 108 connecting vertical elements of the rub collars simultaneously engaged by the patterns. With the foregoing and other desirable requirements to be satisfied, the machine is initially adjusted as hereinafter described.

The plate 254 is moved to and set in its proper position lengthwise of the channel 258 on the angular rest 266 in accordance with the height of the heel block 32 to be operated upon, the rest 266 is moved to and set in its desired angularly adjusted position on the plate in accordance with the pitch of the block, and the end gage 286 (assuming that the heel block has not been pretrimmed to length) is moved to and set in its proper adjusted position on the angular rest, the above adjustments being readily effected by the use of scales 366 (Fig. 6), 368 and 292 respectively.

The bolts 212 are then loosened and the lower portion 206 of the carrier 64 is raised or lowered lengthwise of the axes 66, 68 in accordance with the width of the heel block 32 to be accommodated, the proper adjustment being readily effected by the use of the scale 215. When the bolts 212 have been tightened to secure the upper and lower portions 200, 206 of the carrier 64 together, the work supporting ledge 262 is so positioned that the heel block 32 to be operated upon and positioned in the carrier is centralized widthwise in said carrier. The nut 222 is next rotated to raise or lower with relation to the yoke 67 the carrier 64 as an entirety lengthwise of the axes 66, 68 one-half the distance (determined by reading the scale 219 with reference to a shoulder 350 on said yoke) that the lower portion 206 of the carrier was raised or lowered with relation to said upper portion of the carrier but in an opposite direction. The upper pattern 204 (Fig. 4) or 210 (Fig. 5) is thereafter raised or lowered by raising or lowering the angle bracket 330 along the vertical channel 328 the same distance and in the same direction lengthwise of the axes 66, 68 that the carrier 64 as an entirety has been raised or lowered. The desirable position of the angle bracket 330 along the vertical channel 328 is readily determined by the use of the scale 331. By reason of the above adjustments the work holder 208 and the patterns 204, 210 are centralized properly lengthwise of the axes 66, 68 with relation to the yoke 64 for operating upon the particular work on hand, the transfer axis 186 being included in the longitudinal heightwise median plane 221 of the heel block 32 positioned in the machine.

It will be apparent that when a heel block 32 of a different width from that of the heel block just operated upon is centralized widthwise in the carrier 64 and the carrier has been centralized in the yoke 67 lengthwise of the axes 66, 68 of the plane of the outer face 65 of the heel block 32 lies above or below the axis 72. When this condition exists, and assuming that the machine has been operating upon right work, and that right work is again to be operated upon, the screw 198 is rotated to a position readily determined by the use of a scale 374 (Fig. 2) so that the distance 187 between the tilt axis 72 and the transfer axis 186 is equal to one-half the width of the heel block 32 to be operated upon thereby moving the carrier 64 into such a position that when the particular heel block is positioned in the carrier its outer side 65

will include the tilt axis 72. It will then be necessary to rotate the elongated screw 142 to move lengthwise of the axes 66, 68 (heightwise of the machine) the entire work carrying assembling so as to move the transfer axis 186 substantially into the transverse median plane 129 of the cutter 70.

As above stated, the patterns 204, 210 used in operating upon the particular heel block 32 on hand are so shaped and arranged and so positioned and clamped in the carrier 64 that when they are in engagement with opposed rub collars, the axis 72, which lies in the plane of the outer side 65 of the heel block 32, extends in close proximity to the line 108 and accordingly extends generally lengthwise of the heel block in the vicinity of the outer upper portion of the block being trimmed.

In the event that the machine has been operating upon left work (Fig. 5), the coupling unit 160 being secured to the yoke 64 in one of its two operating positions as shown in Fig. 12, and it is desired to operate upon right work of the same size and style, the operator, after removing the retaining screws 164 from the bores 199 of the dove-tail guide 162 of the coupling unit 160 and removing the latch pin 326 from the notch 316, rotates the coupling unit 180° about the bearing stud 150 and 15 accordingly about the axis 72 as shown in Fig. 11. Such action causes the yoke 67, which remains upright during the "changeover," to be lowered the width of the heel block 32 to be operated upon thereby moving the carrier 64 into such a position that the plane of the outer face 65 (then the uppermost face of the block as shown in Fig. 4) of the heel block 32 to be operated upon and secured to the carrier will substantially include the axis 72. The coupling unit 160 is then secured to the yoke 67 in the other operating position upside down from that shown in Fig. 12, the retaining screws 164 being threaded into opposite bores 199 of the dove-tail guide 162 to secure the yoke 67 to the coupling unit. The latch 170, which has been rendered active by reason of the coupling unit 160 having been rotated 180° about the bearing stud 150, is then slid into such a position that its cylindrical face 172 extends into the notch 178 to limit tilting movement of the coupling unit 160 and accordingly the yoke 67 about the axis 72. The elongated screw 142 is then rotated to a position determined by a scale 376 (Fig. 2) to raise lengthwise of the axes 66, 68 the adjustable supporting slide or bracket 69 and accordingly the entire carriage assembly comprising the coupling unit 160, the yoke 67 and the carrier 64 until the longitudinal heightwise median plane 221 of the heel block 32 which is to be operated upon will be coincident with the transverse median plane 129 of the rotary cutter 70. The screw 322 which yieldingly supports the latch pin 326 is then lowered sufficiently to enable said latch pin to be inserted in the notch 316 and the spring 324 to exert on the yoke a biasing effect sufficient to maintain the yoke, when the machine is not in use, in a substantially vertical position in which the cylindrical end 172 of the latch 170 in the notch 178 is spaced from the sides of the notch.

When the heel block 32 to be operated upon is positioned upon and secured to the carrier 64 the axis 72 lies in the general plane of the upper side 65 (the uppermost face as shown in Fig. 4) of the heel block 32 and the transfer axis 186 of the bearing stud 150 lies substantially in the longitudinal heightwise median plane 221 of the heel block.

After the necessary adjustments have been made in the machine to accommodate the heel block 32 from which the heel 44 is to be formed, the operator places the heel block 32 on the block support or ledge 262 with its bottom in engagement with the backing board 278 and its rear end in engagement with the gage 286 and with his right hand grasps the handle 233 and presses the trigger 265 causing the clamp 202, acted on by the pneumatic pressure means above described, to be forced

against the heel block to secure said block in place in the carrier 64. The operator, while maintaining his hold on the handle 233 and maintaining the trigger 265 depressed, grasps the grip 223 of the bracket 225 with his left hand and swings the carrier 64 simultaneously about the axes 66, 68 causing the exposed upper face portion 30 of the heel block 32 in the carrier 64 to traverse the cutter 70 in a path determined by the sliding engagement of the patterns 204, 210 with the rub collars, the trimming cut starting at the rear end portion of the block and progressing to the forward end of said block, thereby providing the heel block 32 with the attaching face 34. The operator then swings the yoke 67 away from the rotary cutter 70 and after releasing the trigger 265 to render the clamp 202 inactive removes the block 32a from the machine.

Having thus described the invention, what I claim as new and desire to secure by Letters Patent of the United States is:

1. In a machine for use in the manufacture of wedge heels, a cutter rotatable about an axis, rub abutments positioned adjacent to the cutter, a mount journaled for rotation about a fixed axis which is approximately parallel to and is spaced a substantial distance from the axis of the cutter, said mount also being journaled for arcuate movement about a tilt axis which is disposed at approximately right angles to said fixed axis and is constrained for arcuate movement about said fixed axis, a carrier supported by and journaled on the mount for movement about a swing axis which is fixed with relation to the mount and accordingly is constrained for arcuate movement about said tilt axis and which is spaced from and is arranged generally parallel to said fixed axis, means for positioning on and securing to the carrier a wedge heel block with an upper face portion thereof exposed, and patterns which have different profiles and are secured in predetermined positions to the carrier and which are adapted to be slid respectively along the rub abutments to guide said block, which may be freely moved simultaneously about one or more of said axes, past the cutter in a predetermined path to form an attaching face on said block.

2. A machine as defined in claim 1, and further characterized by means for initially positioning with relation to the tilt axis the mount and accordingly the carrier generally lengthwise of said fixed axis.

3. A machine as defined in claim 2, and further characterized by means for initially effecting relative rectilinear adjustment lengthwise of said fixed axis between the cutter and the tilt axis to cause the wood heel block positioned in the carrier to be centralized widthwise with relation to the cutter.

4. In a machine for use in the manufacture of wedge heels, a cutter rotatable about an axis, rub collars arranged at opposite ends of the cutter, a bearing block mounted for movement about one axis, a yoke supported by the bearing block and tiltable upon the bearing block for movement about a tilt axis which is disposed at right angles to said one axis, a carrier pivotally mounted upon the yoke for movement about a second axis parallel to said one axis, pairs of patterns having rub collar engaging faces of different contours, means for securing interchangeably one of said pairs of patterns to the carrier, means for positioning and securing a heel block in the carrier, said carrier being movable simultaneously about said one and second axes to cause said block to traverse the cutter in a predetermined path controlled by the engagement of the patterns with the rub collars to form an attaching face on the heel block, and means adapted to secure the yoke to the bearing block, thereby insuring against tilting of the yoke on the bearing block and accordingly the heel block about said tilt axis as said block moves in said path, and also adapted to release said yoke for movement about the tilt axis thereby allowing the heel block during its movement in said path to tilt in

response to the engagement of the patterns with the rub collars.

5. In a machine for use in the manufacture of wedge heels, a cutter rotatable about a fixed axis, a pair of rub collars spaced axially and at opposite ends of the cutter, a yoke pivoted for movement about one axis which is approximately parallel to and is spaced a substantial distance from the axis of the cutter, a carrier pivoted upon the yoke for movement about a second axis which is spaced from and is parallel to said one axis, means for positioning on and securing to the carrier a heel block with an upper face portion thereof exposed, and patterns which have different profiles and are secured in predetermined positions to the carrier and which, as the carrier is moved simultaneously about said one and second axes, slide respectively along said rub collars to guide said upper face portion of the block past the cutter in a predetermined path extending generally lengthwise of the block thereby forming an attaching face on said block, said yoke also being mounted for rocking movement about an axis which is disposed at right angles to said second axis and which extends generally lengthwise of and in close proximity to a lateral margin of the upper face portion of the block being acted upon by the cutter to enable the carrier to rock laterally through an arc, determined by the action of the rub collars against the patterns, about one of the upper lateral margins of the block during part of the movement of the heel block in said path past the cutter.

20 6. In a machine for use in the manufacture of wedge heels, a cutter rotatable about an axis, rub collars positioned respectively at opposite ends of the cutter, a carrier movable about a pair of spaced parallel axes which are generally parallel to the cutter axes, patterns which are rigidly secured to the carrier and have rub collar engaging faces, said carrier comprising a holder having a ledge lying substantially in a plane and adapted to be engaged by a side of a heel block from which a wedge heel is to be made, means for positioning said block upon and clamping it against said ledge, means for moving the carrier simultaneously about said spaced parallel axes in a path governed by the engagement respectively of said patterns with the rub collars to form on said heel block an attaching face, means for tilting the carrier during a portion of its movement in said path about a tilt axis which is disposed approximately at right angles to and intersects one of said parallel axes and relatively to which the carrier is rotatable about one of said parallel axes and which passes substantially through points of intersection of the plane of the ledge and straight lines extending between points of simultaneous engagement of the patterns with the rub collars, and means for initially moving the carrier into different adjusted positions lengthwise of said parallel axes with relation to said tilt axis to maintain the plane of the ledge in the tilt axis in accordance with the widths of the heel blocks being operated upon.

45 7. In a machine for use in the manufacture of wedge heels, a cutter, means for rotating the cutter, abutments, a carrier, means for securing a heel block in a predetermined position to the carrier with the upper face portion of said block exposed, a pair of patterns, means for rigidly securing said patterns to the carrier, said carrier being movable simultaneously about spaced axes which are approximately parallel to the axis of rotation of the cutter and also about a tilt axis which is disposed at approximately right angles to said spaced axes and relatively to which the carrier is rotatable about one of said spaced axes to move the heel block guided by the engagement of the patterns with the abutments in a predetermined path past the cutter to provide a form fitting attaching face on the heel block, means for moving into different adjusted positions lengthwise of said spaced axes the carrier with relation to the tilt axis, and means for moving the tilt axis into different adjusted positions lengthwise of said spaced axes.

8. In a machine for use in the manufacture of wedge heels, a cutter rotatable about an axis, abutment means, a bearing block mounted for movement about one axis, a yoke supported by the bearing block for movement therewith and movable upon said block about a tilt axis disposed at right angles to said one axis, a carrier pivotally mounted upon the yoke for movement independent of its movement about said one and tilt axes about a second axis parallel to said one axis, a pair of patterns, means for positioning a heel block and the patterns upon and securing them rigidly to the carrier, said carrier being movable about said one, tilt and second axes to cause said block to traverse the cutter in a predetermined path controlled by the engagement of the patterns with the abutment means to form an attaching face on the heel block, and means for moving lengthwise of said one and second axes into different initially adjusted positions the carrier relatively to the yoke and to the tilt axis and the cutter, the yoke relatively to the bearing block and to the cutter and the bearing block relatively to the cutter.

9. In a machine for use in the manufacture of wedge heels, a rotary cutter, abutment means, a bearing block mounted for movement about one axis, a yoke which is supported by the bearing block and is movable therewith and which is tilttable upon said block about an axis disposed at right angles to said one axis, a carrier which comprises upper and lower portions and is pivotally mounted upon the yoke for movement about a second axis arranged parallel to said one axis, a pair of patterns, means for positioning a heel block in the lower portion of the carrier, means for clamping the positioned heel block between the upper and lower portions of the carrier, means for positioning the patterns upon and securing them to the upper and lower portions respectively of the carrier, means connecting for relative adjustment the upper and lower portions of the carrier lengthwise of said one and second axes, said carrier being movable simultaneously about said one and second axes to cause said heel block to traverse the cutter in a predetermined path controlled by the engagement of the patterns with said abutment means to form an attaching face on the heel block, and means for moving lengthwise of said one and second axes, the carrier as an entirety relatively to the yoke and to the cutter, the yoke relatively to the bearing block and to the cutter and the bearing block relatively to the cutter.

10. In a machine for use in the manufacture of wedge heels, a cutter rotatable about a fixed axis, rub collars arranged axially of the cutter at its opposite ends, a bearing block movable about a bearing block axis which is approximately parallel to the cutter axis, a yoke which is carried by the bearing block and is journaled on said bearing block for movement about a tilt axis disposed at approximately right angles to the bearing block axis, a carrier journaled in the yoke for movement about a carrier axis which is parallel to the bearing block axis, means for securing in a predetermined position to the carrier a heel block with an upper face portion thereof exposed, a pair of patterns, means for securing said patterns to the carrier at opposite sides of said heel block, said carrier being movable simultaneously about said carrier and bearing block axes and also about said tilt axis to cause the heel block guided by the engagement of the patterns with the rub collars to move past the cutter in a predetermined path to form in the upper face portion of the block a form fitting attaching face, means for moving into different initially adjusted positions lengthwise of the bearing block axis the yoke with relation to the bearing block and accordingly the tilt axis, and means for moving the bearing block into different initially adjusted positions lengthwise of the tilt axis.

11. In a machine for use in the manufacture of wedge heels, a cutter which is rotatable about a fixed axis and which has a convex cutting edge and a transverse median plane disposed at right angles to said axis, fixed rub col-

lars arranged respectively at opposite ends of the cutter, a carrier which is movable about a pair of spaced parallel axes and comprises two portions, means for positioning and supporting a heel block in one of said portions, a clamp which is carried by the other portion and is adapted to secure said block to said one portion, a pair of patterns which are secured respectively to said portions of the carrier and which have faces for engaging respectively the rub collars, means for moving about said spaced parallel axes the carrier in a predetermined path controlled by the engagement of the patterns with the rub collars to remove material from an upper face portion of the block to form an attaching face on said block, means for effecting adjustment between said one portion of the carrier and said other portion of the carrier lengthwise of said parallel axes to accommodate in the carrier heel blocks of different widths, means for adjusting the carrier as an entirety lengthwise of said parallel axes with relation to the transverse median plane of the cutter to centralize widthwise heel blocks of different widths positioned in the carrier, means for moving into different adjusted positions in directions parallel to said parallel axes, said second pattern to centralize said second pattern widthwise of the block, and means for tilting during the forming of the attaching face of the block the carrier about an axis disposed approximately at right angles to said parallel axes and passing through one of said parallel axes.

12. In a machine for use in the manufacture of wedge heels, a cutter which is rotatable about a fixed axis and which has a convex cutting edge and a transverse median plane disposed at right angles to said axis, fixed rub collars arranged respectively at opposite ends of the cutter, a yoke, a carrier which is pivotally mounted upon the yoke for movement about a carrier axis and which comprises upper and lower portions, means for pivotally supporting the yoke for movement about an axis which is parallel to and spaced from the carrier axis, means for positioning and supporting a heel block in the lower portion of the carrier, a clamp carried by the upper portion of the carrier for securing the heel block to the lower portion of the carrier, a pair of patterns one of which is secured to the lower portion of the carrier and the other of which is secured to the upper portion of the carrier, said patterns having faces for engaging respectively the rub collars, means for effecting an adjustment of said lower portion of the carrier lengthwise of the carrier axis with relation to the upper portion of the carrier to accommodate heel blocks of different widths, means for adjusting the carrier as an entirety in the yoke lengthwise of the carrier axis to centralize the heel block widthwise with relation to the yoke, means for moving into different adjusted positions in directions parallel to the carrier axis said other pattern to arrange it a predetermined distance from the heel block irrespective of the width of the block, means for moving simultaneously about the carrier axis and the axis of rotation of the yoke the carrier in a predetermined path governed by the engagement of the patterns with the rub collars to remove material from an upper face portion of the block to form an attaching face on the block, means for tilting during the forming of the attaching face on the block the carrier about a tilt axis disposed at approximately right angles to the axis of rotation of the yoke, and means for adjusting with relation to the tilt axis the yoke lengthwise of its axis of rotation to position the heel block widthwise with relation to said tilt axis.

13. In a machine for use in the manufacture of wedge heels, a cutter rotatable about an axis, rub collars arranged lengthwise of the cutter axis at opposite ends respectively of the cutter, a supporting bracket, a bearing block pivotally mounted on said bracket for movement about one axis, a yoke, a coupling unit comprising one portion which is journaled by a pivotal connection to the yoke for movement about an adjusting axis and a second portion of which is pivotally mounted upon the bearing

block for movement about a tilt axis arranged parallel to said adjusting axis, interlocking means for rigidly securing said one portion of the coupling unit to the yoke and for disconnecting said one portion of the coupling unit from the yoke preparatory to pivotally adjusting said unit between two different operating positions on the yoke, a carrier pivotally mounted upon the yoke for movement about a second axis which is parallel to said one axis, means for positioning and securing a heel block in the carrier, spaced patterns secured to the carrier, said carrier being movable simultaneously about said one and second axes to move said heel block in a predetermined path controlled by the engagement of the patterns with the rub collars respectively to form an attaching face upon said block, said carrier being movable about said tilt axis as it moves in said predetermined path to tilt the heel block laterally, means for moving said one part of the coupling unit relatively to the other part of the unit into different adjusted operating positions toward and away from said tilt axis to move the pivotal connection between said one portion of the unit and the yoke and accordingly the adjusting axis toward and away from the tilt axis, said coupling unit being movable about the tilt axis to move the yoke selectively into either one of said different operating positions in which said adjusting axis is positioned equal distances from and at diametrically opposite sides of the tilt axis and in which the yoke is secured to said one portion of the unit by said interlocking means, and means for moving said supporting bracket into different positions lengthwise of said one and second axes.

14. In a machine for use in the manufacture of wedge heels, a cutter which is rotatable about a fixed axis and has a transverse median plane, rub collars arranged at opposite ends of the cutter, a carrier for a heel block, said carrier comprising upper and lower portions having alined trunnions respectively, a yoke having alined bores for receiving said trunnions and for pivotally supporting the carrier for movement about an axis of the trunnions, a bearing block upon which the yoke is mounted and which is journaled for movement about a bearing block axis substantially parallel to the axis of the trunnions, said yoke being journaled upon the bearing block for movement about a tilt axis disposed at substantially right angles to said bearing block axis, means connecting for relative adjustment the upper and lower portions of the carrier to accommodate heel blocks of different widths from which heels of different sizes and styles are to be formed, means for positioning the heel block in and clamping it to the carrier, a pair of patterns, means for positioning and securing the patterns to the upper and lower portions of the carrier, means for adjusting one of the patterns lengthwise of the axis of the trunnions into different adjusted positions with relation to the heel block to centralize the patterns in the carrier with relation to the block, means for adjusting the carrier as an entirety lengthwise of the trunnion axis to centralize the carrier in the yoke and to move a longitudinal heightwise median plane of the heel block into approximate coincidence with the transverse median plane of the cutter, and means for adjusting the yoke generally lengthwise of the trunnion axis with relation to the bearing block to vary the distance between the longitudinal heightwise median plane of the heel and the tilt axis.

15. In a machine for use in the manufacture of wedge heels, a cutter which is rotatable about a fixed axis and has a transverse median plane, rub collars arranged at opposite ends of the cutter, a carrier for a heel block, said carrier comprising upper and lower portions having alined trunnions respectively, a yoke having alined bores for receiving said trunnions and for pivotally supporting the carrier for movement about an axis of the trunnions, a bearing block upon which the yoke is mounted and which is journaled for movement about a bearing block axis substantially parallel to the axis of the trunnions,

said yoke being journaled upon the bearing block for movement about a tilt axis disposed at substantially right angles to and intersecting said bearing block axis, means connecting for relative adjustment the upper and lower portions of the carrier to accommodate heel blocks of different widths from which heels of different sizes and styles are to be formed, means for positioning the heel block in and clamping it to the carrier, a pair of patterns, means for positioning and securing the patterns to the upper and lower portions respectively of the carrier, means for adjusting one of the patterns lengthwise of the axis of the trunnions into different adjusted positions with relation to the heel block to centralize the patterns in the carrier with relation to the block, means for adjusting the carrier as an entirety lengthwise of the trunnion axis to centralize the carrier in the yoke and to move a longitudinal heightwise median plane of the heel block into approximate coincidence with the transverse median plane of the cutter, means for adjusting the yoke generally lengthwise of the trunnion axis with relation to the bearing block to vary the distance between the longitudinal heightwise median plane of the heel and the tilt axis, and means for locking the yoke to the bearing block to secure the yoke against movement about the tilt axis and for releasing the yoke for movement about said tilt axis upon the bearing block.

16. In a machine for use in the manufacture of wedge heels, a cutter which is rotatable about an axis and has a transverse median plane, a pair of rub collars arranged at opposite ends of the cutter, a carrier, a pair of patterns, means for securing in a predetermined position to the carrier a heel block having planar sides which are approximately parallel and a longitudinal heightwise median plane, means for securing the patterns in predetermined positions to the carrier at opposite sides respectively of the heel block, a yoke, means for journaling the carrier in the yoke for movement about a carrier axis arranged approximately parallel to the axis of the cutter, means for adjusting the carrier in the yoke lengthwise of the carrier axis to centralize the heel block in the carrier with its longitudinal median plane substantially coincident with the transverse median plane of the cutter, a bearing block movable about a bearing block axis which is parallel to the carrier axis, a coupling unit one portion of which is secured to the yoke and a second portion of which is pivoted upon the bearing block for movement about a tilt axis which is disposed at substantially right angles to the bearing block and the carrier axes, means for adjusting said one portion of the coupling unit relatively to said second portion of the unit lengthwise of the bearing block and the carrier axes to move the heel block into such a position that a plane of one of its sides includes the tilt axis, and means for moving the bearing block lengthwise of the bearing block and the carrier axes to reposition the heel block with its lengthwise longitudinal median plane in substantial coincidence with the transverse median plane of the cutter.

17. In a machine for use in the manufacture of wedge heels, a cutter which is rotatable about an axis and has a transverse median plane, a pair of rub collars positioned at opposite ends of the cutter, a carrier, a pair of patterns, means for securing a heel block, which has planar parallel sides and a longitudinal heightwise median plane, in a predetermined position to the carrier, means for rigidly securing the patterns in predetermined positions to the carrier, a yoke, means for journaling in the yoke the carrier for movement about a carrier axis, means for adjusting the carrier lengthwise of its axis in the yoke to move the longitudinal heightwise median plane of the heel block into approximate coincidence with the transverse median plane of the cutter, a bearing block pivoted about a fixed axis which is parallel to the carrier axis, a coupling unit comprising one portion which is pivotally connected to the yoke for movement about a transfer axis and a second portion which is pivotally supported on the bearing block

for movement about a tilt axis which is parallel to said transfer axis and is arranged at right angles to and passes through said fixed axis, means for rigidly securing to the yoke said one portion of the coupling unit in different operating positions, in which the coupling unit is displaced 180° about the tilt axis and in which the transfer axis is arranged equal distances at diametrically opposite sides of the tilt axis, and for releasing said one portion of the coupling unit and accordingly said unit for rotation about the tilt axis between said two different operating positions, means for adjusting said one portion of the coupling unit secured to the yoke in one of its two different operating positions lengthwise of said fixed axis relatively to said second portion of the unit to move the yoke lengthwise of said fixed axis with relation to the tilt axis until the distance between the transfer and the tilt axes is equal to one-half the width of the heel block thereby moving a general plane of one of the sides of the heel into substantial coincidence with the tilt axis, said coupling unit being mounted for swinging movement about said tilt axis from one to the other of its two operating positions in which it may be rigidly secured to the yoke thereby displacing the yoke lengthwise of said axis by twice the distance between the transfer and the tilt axes and thus moving a general plane of the opposite side of the block in the carrier into approximate coincidence with the tilt axis, and means for moving the bearing block lengthwise of said fixed axis to move the tilt axis and the yoke as an entirety until the longitudinal heightwise median plane of the heel block coincides substantially with the transverse median plane of the cutter.

18. In a machine for use in the manufacture of wedge heels, a rotary cutter, rub abutments arranged adjacent to the cutter, a carrier, means for positioning in and securing to the carrier a heel block which has planar sides and from which a wedge heel is to be formed, said carrier

being movable about spaced parallel axes and about a tilt axis arranged at right angles to said axes, patterns rigidly secured to the carrier and adapted to engage the rub abutments to guide the carrier in a predetermined path about said parallel axes and about said tilt axis, and means for adjusting relatively to said tilt axis the carrier lengthwise of said parallel axes to move the heel block into such a position that a plane in which one of its sides lies includes the tilt axis.

19. In a machine for use in the manufacture of wedge heels, a rotary cutter, rub abutments arranged adjacent to the cutter, a carrier, means for positioning in and securing to the carrier a heel block which has planar sides and from which a wedge heel is to be formed, said carrier being movable about spaced parallel axes and about a tilt axis arranged at right angles to said axes, patterns rigidly secured to the carrier and adapted to engage the rub abutments to guide the carrier in a predetermined path about said parallel axes and about said tilt axis, means for adjusting relatively to said tilt axis the carrier lengthwise of said parallel axes to move the heel block into such a position that a plane in which one of its sides lies includes the tilt axis, mechanism for adjusting relatively to the tilt axis the carrier lengthwise of said parallel axes in opposite directions a distance equal to the width of the heel block, and mechanism for moving the tilt axis lengthwise of said parallel axes.
